3 Claims. (Cl. 208—211)

This invention relates to a process for the removal of sulfur from liquid hydrocarbon streams, particularly petroleum residua. More specifically, the invention relates to an integrated two-stage desulfurization process comprising chemical desulfurization in the first stage and hydrodesulfurization in the second stage.

Generally, sulfur occurs in petroleum stocks in one of the following forms: mercaptans, sulfides, disulfides and as part of a more or less substituted ring of which thiophene, benzothiophene and dibenzothiophene are the prototypes. The mercaptans are generally found in the lower boiling fractions, e.g. the naphtha, kerosene, and light gas oil. Numerous processes for sulfur removal from these lower boiling fractions have been suggested, such as "doctor" sweetening (wherein mercaptans are converted to disulfides), caustic treating, solvent extraction, copper chloride treating, etc., all of which give a more or less satisfactory decrease in sulfur or inactivation of mercaptans by their conversion into disulfides. When the process results in the latter effect, the disulfides generally remain in the treated product and must be removed by another step if it is desired to obtain a sulfur-free product.

Sulfur removal from higher boiling fractions, however, has been a much more difficult operation. Here the sulfur is present for the most part in the less reactive forms as sulfides, disulfides and as a part of a ring compound, such as thiophenes, benzothiophenes and dibenzothiophenes. Such sulfur is, of course, not susceptible to chemical operations satisfactory for removal of mercaptans. Extraction processes employing sulfur-selective solvents are also unsatisfactory because the high boiling petroleum fractions contain such a high percentage of sulfur-containing molecules. For example, even if a residuum contains only about 3% sulfur it is estimated that substantially all the molecules may contain sulfur. Thus, if such a residuum were extracted with a solvent selective to sulfur compounds the bulk of the residuum would be extracted and lost.

Metallic contaminants, such as nickel and vanadium compounds, are found as innate constituents in practically all crude oils. These contaminants present another problem. Upon fractionation of the crudes, the metallic contaminants are concentrated in the residua which normally have initial boiling points of about 500° F. Such residua are conventionally used as heavy fuels, and it has been found that the metal contaminants therein adversely affect the combustion equipment in which the residua are burned. The contaminants not only form scale, which leads to sludging and the formation of deposits upon boiler tubes, combustion chamber walls, and gas turbine blades, but also attack the refractories which are used to line boilers and combustion chambers and severely corrode boiler tubes and other metallic surfaces with which they come into contact at high temperatures.

The nitrogenous compounds are found in many crude oils to a varying extent depending on the source. These compounds are objectionable primarily due to (1) their tendency to promote instability in the finished, marketable products, such as gasoline, kerosene, heating oil, jet fuels and the like regardless of whether these are obtained by simple distillation procedures or by cracking heavier frac-

2

tions and (2) due to their adverse effects on the activity of catalytic materials used in cracking reactions, etc.

In the past, methods to chemically remove the sulfur have been ineffective to remove large amounts of sulfur and furthermore, had little or no effect on the nitrogenous or metallic impurities, these materials requiring other methods for their removal.

A process for the chemical desulfurization of residuum stocks employing fused alkali metal hydroxides has been disclosed by Mattox in U.S. Patent 3,164,545 issued Jan. 5, 1965. The disclosed process is also effective to remove nitrogen compounds and metallic contaminants. While contaminant removal is excellent using fused alkali metal hydroxides, the process suffers from the inherent defect that the treating agent becomes spent and it must be regenerated.

Process for hydrodesulfurizing oils in the presence of a catalyst are well known in the petroleum refining art. It is also well known that most of the present processes are limited to feeds which contain low amounts of sulfur, and nitrogen compounds and metal contaminants. Such pretreatments as solvent deasphalting and vacuum distillation are used to reduce sulfur, nitrogen and metals to a level so that the hydrodesulfurization catalyst is not rapidly poisoned.

The object of this invention is to provide a process for the desulfurization of heavy oils which does not require extensive feed conditioning or expensive and complicated pretreating steps. It is another object of this invention to provide a combined chemical desulfurization-hydrodesulfurization process in which the disadvantages of each type of treatment are alleviated by coordinating the two treatments.

We have found that essentially untreated heavy oils such as whole crude oils, topped crude oils, atmospheric residua, shale oils and the like can be treated with fused alkali metal hydroxides to remove a considerable amount of the sulfur and nitrogen compounds and the metal contaminants and the partially refined hydrodesulfurized without rapid poisoning of the catalyst. Furthermore we have found that the H₂S formed in hydrodesulfurization can be used to regenerate the spent alkali metal hydroxide treating agent.

The invention will be further illustrated by the accompanying drawing which is a schematic flow sheet showing a preferred method for practicing the process of the invention.

Reference numeral 1 denotes a line supplying a feed of the type described above to chemical desulfurization zone 2. A typical feed is Kuwait 450° F. topped crude, i.e. material boiling less than 450° F. has been removed from the crude by distillation at atmospheric pressure. The fused alkali metal hydroxide treating agent, KOH for example, is added to zone 2 by line 3. The quantity of KOH will range from 5 to 100 wt. percent based on the feed. The preferred quantity of KOH ranges from 5 to 30 wt. percent.

The amount of water in the molten alkali metal hydroxide is important for the improved results of the instant invention. The water content should be within the range of about 5 to 30 wt. percent based on total reagent, preferably 7 to 25 wt. percent, and more preferably 10 to 20 wt. percent. The most preferred water content is about 15 wt. percent, based on molten alkali metal hydroxide. Temperature conditions during the contacting step should be maintained within the range of 400° to 800° F., preferably 450° to 750° F., more preferably 500° to 700° F. Treating time may be as little as 1/10 hour to 16 hours, generally the longer the time of contact, the greater the impurity removal. Generally, treating times within the range of 1/4 to 6 hours are used. The preferred treating time per stage will be 1/2 to about 2 hours. The pressure

may vary from 0 to 500 p.s.i.g., depending on the hydrocarbon feedstock, and is not critical to the desulfurization reaction.

A small quantity of hydrogen produced in the treating step is removed by line 4 for use in the process or for other refinery operations.

The mixture of KOH and treated residuum leaves the treating zone through line 5 and is mixed with about 0.5 to 3 weights of water per weight of treating agent used and passes to separator 7. The separator can be a conventional settler in which the mixture of molten alkali metal, the reaction products of the feed impurities with the treating agent, and the water separate as a distinct phase from the treated residuum.

The treatment with KOH removes from 10-60% of the sulfur and a major amount of the nitrogen and metal contaminants from the oil. A Kuwait topped crude was treated with 100 wt. percent KOH at 650° F. for 4 hours resulting in a decrease of sulfur content from 2.9 wt. percent to 2.1 wt. percent and vanadium content was reduced from 31 p.p.m. to 2.5 p.p.m. It is the consensus of experts that it is the metals, especially the vanadium found in many crude oils which severely limit catalyst life in treating residuum and thereby makes hydrodesulfurization of untreated residua impractical. Therefore, it can be seen that the molten alkali metal treating step of the invention which removes both sulfur and metals is a valuable tool for preparing stocks for hydrodesulfurization.

The demetallized and partially desulfurized residuum is then passed by line 8 to hydrodesulfurization zone 9. Hydrogen is added by lines 10 and 11. The hydrodesulfurization treatment is carried out in the conventional manner with known catalysts. Desulfurized product is removed by line 12. Suitable process conditions are:

Feed rate, v.v./hr. -----	0.2 to 2.0
Hydrogen rate, s.c.f./bbl. -----	500 to 6000
Pressure, p.s.i.g. -----	300 to 3000
Temperature, ° F. -----	550 to 900

Preferred catalysts are 5-15 wt. percent molybdena on porous alumina and mixtures of cobalt oxide (3-6 wt. percent) with molybdenum oxide (6-12 wt. percent) on adsorptive alumina. Catalysts containing nickel, chromia, platinum, and tungsten in the form of metals, oxides and sulfides on alumina, charcoal, kieselguhr, and bauxite can be used as well.

A gas comprising H₂ and H₂S is carried overhead from the hydrodesulfurization zone by line 13 and the H₂S is removed by a conventional gas separation process such as amine scrubbing in scrubber 14. Hydrogen is recycled by lines 15 and 11.

From 20-95% of the sulfur in a topped crude can be removed by the two-stage treating process of our invention. If desired, more severe hydrodesulfurization conditions can be employed since the metals have been removed from the hydrodesulfurization feed.

H₂S from the gas scrubber 14 is passed by line 16 to zone 17 for use in regeneration of the spent alkali metal treating agent from the first treating step. When KOH is used as the treating agent, the spent material contains unreacted KOH, K₂S, K₂CO₃ and water. Considering the KOH, K₂S and K₂CO₃ as a basis the K₂CO₃ constitutes from 10 to 65 wt. percent of these materials. It is the most difficult material to regenerate. The spent material is passed by line 18 to regeneration zone 17 and contacted with H₂S at a temperature ranging from 200° to 750° F. and at atmospheric, subatmospheric, or elevated pressures, preferably 1 to 500 p.s.i.a. An excess of H₂S based on the K₂CO₃ and K₂S is employed. The carbonate and the K₂S are converted to KSH by this regeneration treatment according to the following reaction:

CO₂ is removed by line 19. A 35 wt. percent aqueous solution of K₂CO₃ was contacted by bubbling H₂S through the solution at 217° F. and atmospheric pressure. The off gas contained 50% CO₂ demonstrating a conversion of 78%. This result was unexpected since H₂S is weaker acid than CO₂ (a.q.).

In the aforementioned regeneration step K₂S is converted to KSH.

A stream containing KSH, and water is passed by line 20 to a second regeneration zone 21 in which the KSH is converted to KOH, the desired alkali metal hydroxide chemical desulfurization agent. This conversion can be accomplished by a number of methods, one of which comprises treating with steam at a temperature ranging from 400 to 1000° F. Steam is introduced to zone 21 by line 22. Unreacted steam and H₂S are removed by line 26. Regenerated KOH is passed by line 23 to H₂O adjustment zone 24. In zone 24 the water content of the KOH treating agent is adjusted to a range of about 5 to 30 wt. percent based on the total reagent used in zone 2. The treating agent is then recycled by line 25 and 3 to the treating zone. Frequently it is desirable to follow the steaming step with a treatment of the caustic solution by a metal or metal oxide such as Cu or CuO, Fe or Fe₂O₃ etc. to ensure good removal of the sulfur and complete caustic regeneration.

Thus it can be seen that the present invention discloses a two-stage desulfurization system in which the chemical desulfurization stage benefits the hydrodesulfurization stage by removing metals, nitrogen, and sulfur and the hydrodesulfurization stage benefits the chemical desulfurization stage by providing H₂S for regeneration of the molten alkali metal treating agent.

The overall process provides the capability of desulfurizing sulfur containing feedstocks without the necessity for extensive pretreating such as deasphalting and vacuum distillation.

The products of the present invention can be used as industrial fuels, as feed to catalytic cracking processes and as feed to hydrocracking process or in any other area of utility where it is mandatory that the stock being used or treated be low in sulfur, nitrogen and metals content.

The molten alkali metal hydroxides suitable for use in carrying out the process of the invention include molten sodium hydroxide, potassium hydroxide, lithium hydroxide, cesium hydroxide and the like. KOH is the preferred treating agent and it can be promoted with any of the aforementioned alkali metal hydroxides.

In a particularly preferred embodiment of the invention, the molten alkali metal having the aforementioned water content of 5 to 30 wt. percent is employed in the presence of an oxygen-containing gas. It has been found that the addition of oxygen during the chemical desulfurization stage results in a surprising increase in the amount of contaminants removed from the residuum. Generally it is preferred to supply the oxygen by bubbling air or a similar oxygen-containing gas through the feed during treatment with the fused hydroxide. When air is used, air rates of from 1 to 1500 standard cubic feet per barrel of residuum can be used. Spargers, distribution plates or other conventional means, not shown in the drawing can be used to promote contacting of the oxygen and the oil.

In a further modification of the present invention the alkali metal bisulfide treated in zone 21 is converted to the alkali metal hydroxide phase by contacting the alkali metal bisulfide at temperatures ranging from 200-1000° F. with a finely-divided metal (M₂), metal oxide (M₂O) or metal hydroxide (M₂OH). The metal sulfides can be converted back to the metals, metal oxides or hydroxides by known methods. Suitable metals include copper, nickel, iron, manganese, cobalt, calcium, magnesium, molybdenum, lead, tin and zinc. Oxides or hydroxides of these metals would also be suitable. Copper and iron and the oxides and hydroxides thereof are the preferred metals.

Where their use is deemed advisable solvents, diluents and solutizers can be used to thin the residuum so that contacting will be more complete.

The molten alkali metal treating stage and the hydrodesulfurization stage of the process can be carried out in a batchwise or in a continuous manner. A continuous process is preferred. Recycle of process streams or treating agents to the various treating or regeneration steps is to be considered within the scope of the invention.

Other obvious variations of the process which would occur to those skilled in the art are intended to be included in the scope of the disclosure and the claims.

What is claimed is:

1. In a two-stage process for desulfurizing whole atmospheric residuum having an initial boiling point of about 450° F. and containing sulfur, nitrogen and metallic contaminants comprising contacting said residuum in a first stage with molten potassium hydroxide treating agent containing 5 to 30 wt. percent water based on the total reagent at a temperature in the range of 400-800° F. and then hydrotreating the partially desulfurized residuum in the presence of a cobalt molybdate catalyst at a temperature ranging from 550 to 900° F., a pressure ranging from 300 to 3000 p.s.i.g., a hydrogen charge rate of 500 to 6000 s.c.f./bbl. of residuum and a space velocity of 0.2 to 2.0 volumes of residuum per hour per volume of catalyst, the improvement comprising regenerating spent treating agent from the first step containing K_2CO_3 and K_2S by contacting the spent treating agent with H_2S recovered from the hydrotreating step, contacting the partially regenerated treating agent containing KSH with steam at a temperature ranging from 400 to 1000° F. to convert the KSH to KOH and recycling the regenerated KOH to the first stage.

2. In a two-stage process for desulfurizing whole atmospheric residuum having an initial boiling point of about 450° F. and containing sulfur, nitrogen and metallic contaminants comprising contacting said residuum in a first stage with molten potassium hydroxide treating agent containing 5 to 30 wt. percent water based on the total 40

reagent at a temperature in the range of 400-800° F. and then hydrotreating the partially desulfurized residuum in the presence of a cobalt molybdate catalyst at a temperature ranging from 550 to 900° F., a pressure ranging from 300 to 3000 p.s.i.g., a hydrogen charge rate of 500 to 6000 s.c.f./bbl. of residuum and a space velocity of 0.2 to 2.0 volumes of residuum per hour per volume of catalyst, the improvement comprising regenerating spent treating agent from the first step containing K_2CO_3 and K_2S by contacting the spent treating agent in a first regeneration zone with H_2S recovered from the hydrotreating step, contacting the partially regenerated treating agent in a second regeneration zone with a finely divided solid compound selected from the group consisting of Me, MeO, MeOH, wherein Me is selected from the group consisting of copper, nickel, iron, manganese, cobalt, calcium, magnesium, molybdenum, lead, tin and zinc, and recycling the regenerated KOH to the first stage.

3. A two-stage process for removing sulfur, nitrogen and metal impurities from a topped crude oil having an initial boiling point of about 450° F. comprising the steps of contacting the oil with a treating agent consisting of molten alkali metal hydrogen containing 5 to 30 wt. percent water at a temperature in the range of 400-800° F., hydrodesulfurizing the partially purified oil at a temperature in the range of 550-900° F. in the presence of 500-6000 s.c.f./bbl. of hydrogen and a hydrodesulfurization catalyst, recovering desulfurized oil, and employing H_2S recovered from the hydrodesulfurization step in the regeneration of the treating agent when it has become spent.
